UNITED STATES PATENT OFFICE.

WILLIAM SIPES, OF SHELBYVILLE, INDIANA.

RAIL JOINT.

Application filed December 9, 1926. Serial No. 153,648.

This invention relates to a rail joint, the general object of the invention being to provide a spring clamp for connecting the ends of two rails together with a casing-like supporting member for receiving a portion of the clamp and which is adapted to be fastened to a pair of ties.

A further object of the invention is to so form the clamp that the weight of a train 10 on the rails will cause the clamp to grip more firmly the ends of the rails and thus prevent relative movement of the rails or spreading of the rails.

Another object of the invention is to provide a tool for spreading the two parts of 15 the clamp in order to remove the rails or insert them in the clamp.

This invention also consists in certain other features of construction and in the 20 combination and arrangement of the several parts, to be hereinafter fully described, illustrated in the accompanying drawings and specifically pointed out in the appended claims.

25 In describing my invention in detail, reference will be had to the accompanying drawings wherein like characters denote like or corresponding parts throughout the several views, and in which:—

30 Figure 1 is a plan view of the device showing the same in use and with the rail webs in section.

Figure 2 is a longitudinal sectional view 35 through the device with the rails in elevation.

Figure 3 is a section on line 3—3 of Figure 2.

Figure 4 is a fragmentary bottom plan 40 view showing the hinge construction of the clamp.

As shown in these views, I provide a casting-like supporting member 1 which has extensions at its ends which are adapted to rest upon a pair of ties A and to be spiked 45 to the ties by spikes passing through the notches 2 formed in the extensions. As seen, the supporting member bridges the space between two ties and the rail joint is arranged above said space. Each end of each 50 rail B is formed with a pair of holes 4 so that the four holes in the abutting ends of a pair of rails will come above the chamber formed in the supporting member 1. The clamp is composed of two sections 6 and 7 55 which are hingedly connected together at their lower ends by having a rod 8 passing

through the laterally extending tongues 9, the tongues of one section lying in recesses formed between the tongues of the other section. Springs 10 are placed on the rod 60 8 and are fastened to the tongues in such a manner that the said springs will tend to hold the clamp in closed position. The tongues are formed on straight depending portions 11 of the sections and the upper 65 part of each section is shaped to engage one side of the base and one wall of the web of a rail, the upper end of each section coming under the head of the rail. The upper parts of the sections are formed with the 70 inwardly extending projections 12 which are adapted to pass through the holes 4 in the rails.

The clamp is opened and the abutting ends of a pair of rails placed therein so that 75 the holes will register with the projections 12. Thus when the clamp is closed, the projections will enter the holes, as shown in Figure 1, and the two sections of the clamp will engage the rail ends through means 80 of the spring pressure. The parts 11 of the clamp are then placed in the chamber formed in the member 1 or the rails can be placed in the clamp while the same is resting in the said chamber. In order to permit the clamp to be opened while in engagement with the supporting member, I provide grooves 13 in the side flanges 14 of the supporting member which will permit the rounded outer 85 portions of the sections to move downwardly a sufficient distance to permit the clamp to open so that the rails can be placed therein. After the rails are put in place they are 90 spiked down in the usual manner and this will hold the clamp in its supporting member and the rail ends cannot be separated 95 from the clamp or the clamp withdrawn from its supporting member until the spikes are removed to permit the rail ends to be lifted sufficiently to open the clamp or to remove it from its supporting member.

I provide wear plates 15 on the end extensions of the member 1 upon which the rails rest, each plate having a guiding rib 16 at each side thereof for engaging the 100 edges of the base of a rail.

In order to permit the clamp to be opened, I provide a pair of members 17, one of which is provided with a threaded hole through which a threaded shaft 19 passes, the end of 105 the shaft being fastened to the other member so that when the shaft is turned by its

handle 20, the members will either be moved apart or toward each other according to the direction of movement of the shaft. A guiding pin 21 is carried by one member and passes through a hole in the other member to keep the members in alignment. Each member is provided with a depending part 22 which is adapted to be placed in a handle-like loop 23 fastened to each section of the 10 clamp so that as the members are moved apart they will open the clamp, as will be understood.

From the foregoing, it will be seen that the supporting plate is fastened to a pair of 15 ties and then the clamp is opened by the opening tool to permit the rail ends to be placed therein. As before stated, the clamp can be fastened to the rails before being placed in the supporting member or it can 20 be connected with the rails while being supported by said member. As the jaws of the tool are moved toward each other, the springs will cause the sections of the clamp to close and thus grip the rails. The rails 25 are then spiked to the ties. Thus I have provided simple means for fastening the rail ends together and such means will firmly hold the rails in place.

It is thought from the foregoing description that the advantages and novel features 30 of my invention will be readily apparent.

I desire it to be understood that I may make changes in the construction and in the combination and arrangement of the several 35 parts, provided that such changes fall within the scope of the appended claims.

What I claim is:

1. A rail joint comprising a supporting member having a chamber therein, a clamp for clamping together the abutting ends of a pair of rails, said clamp having a depending portion fitting in the chamber which acts to hold the clamp in closed position and when the rails are spiked down the clamp will be held in this chamber. 40

2. A rail joint comprising a supporting member having a chamber therein and adapted to bridge the space between two ties with its ends fastened to the ties, a clamp for clamping together the abutting ends of a pair of rails, said clamp having a depending portion fitting in the chamber which acts to hold the clamp in clamping position and when the rails are spiked down the clamp will be held in this chamber, said clamp comprising two sections hinged together and spring means for holding the clamp in closed position. 50

3. A rail joint comprising a supporting member having a chamber therein, a clamp for clamping together the abutting ends of a pair of rails, said clamp having a portion fitting in the chamber so that when the rails are spiked down the clamp will be held in this chamber, said clamp comprising two sections hinged together, spring means for holding the clamp in closed position and each section having projections thereon for engaging holes in the rails. 55

In testimony whereof I affix my signature.

WILLIAM SIPES.
